UNITED STATES PATENT OFFICE.

JACOB E. NEAHR, OF BOSTON, MASSACHUSETTS.

MATCH-SAFE.

No. 800,870.

Specification of Letters Patent.

Patented Oct. 3, 1905.

Application filed April 7, 1903. Serial No. 151,517.

To all whom it may concern:

Be it known that I, JACOB E. NEAHR, a citizen of the United States, and a resident of Boston, Suffolk county, Massachusetts, have invented certain new and useful Improvements in Match-Safes, of which the following is a specification.

This invention relates to match-safes, and is intended to provide a receptacle for matches and conveniently arrange with reference thereto a strip of igniting material supported to be struck by the matches so as to be capable of frequent adjustment or renewal as the igniting-surface becomes worn away.

The invention comprises generally a match-receptacle, a coiled strip of igniting material supported in convenient relationship to said receptacle, and a spring arranged to press upon the outside of the coiled strip toward the center thereof in order to hold the strip in place while permitting its frequent adjustment. These and other specific features of my invention will be particularly described in the following specification.

In the drawings I have shown one of the various forms under which my invention may be embodied.

Figure 1 is a front elevation of the entire device. Fig. 2 is a side elevation. Fig. 3 is a side elevation in vertical section. Fig. 4 is a horizontal plan view taken below the match-receptacle. Fig. 5 is a side elevation with the strip-holder in the open position which it occupies when a new strip is to be inserted. Fig. 6 is a rear elevation of the entire device.

This invention is intended to provide a simple and inexpensive means for holding the coil ignition-strip adjustably in place as the size or thickness of the coil decreases owing to the consumption of the igniting material.

The device in the form herein shown comprises generally a back *a*, to which is secured the match receptacle or pocket *b*, beneath which is arranged the spirally-coiled igniting-strip *c*, which rests upon the supporting ledge or shelf *d*, which in this case is pivotally or hingedly connected to the back plate. The flexible ignition-strip *c* may for convenience be wound about a central core or spool *c'* to any desired thickness which the capacity of the holder will permit. The front wall of the match-receptacle *b* is provided with a small depending ledge or lip *b'*. The support *d* is provided with a similar upwardly-projecting lip or flange *d'*, which serves as a stop

to limit the forward movement or position of the coiled strip *c*. To prevent the coil from unwinding, I have provided a keeper *f*, which has a spring portion *f'* secured to the back plate and a clamping member or finger *f''* of approximately circular shape to surround and clamp a portion of the strip *c*. The spring-tongue *f'* is so positioned that it exerts a tension which tends to force the clamping member *f''* forward toward the center of the strip or core upon which the strip may be wound. When the greatest length of strip is wound upon the core, the clamping member *f''* will be bent back so as to nearly coincide with the line of the spring *f'*. As pieces of the igniting material are torn off the clamp is advanced under the tension of the spring *f'* so as to exert a firm grip or pressure against the coiled material until it is exhausted, the coiled strip being moved forward until its front face comes in contact with the flanges *b' d'*.

For convenience in inserting fresh strips of the igniting material the strip-support *d* is here shown hingedly connected to the back plate. This may be accomplished in a very simple manner by offsetting or forming a lip at the lower end of the plate *a*, as shown at *a'*, and by forming at suitable distances apart two vertical slots, as shown at *a''*, in the back plate. This arrangement of the slots forms a spring-tongue *a''*. The bottom plate or support *d* is formed with an upturned flange *d''* somewhat longer than the width of the tongue *a''*, so that its two ends may be inserted into the slots *a''*. The natural resiliency or elasticity of the metal back tends to keep this flange *d''* in a vertical position, and hence to keep the main bottom plate *d* in a horizontal position. When it is desired to substitute a new strip, the front end of the plate *d* is depressed until the parts occupy the position shown in Fig. 5, thus permitting a new strip to be wound about the core and placed in position against the front of the clamp *f''*, after which the plate *d* may be sprung back into its horizontal position, so as to clamp or press the coiled strip *c* and its core *c'* upward against the bottom of the match-receptacle *b*.

As this device is constructed it is made of but four parts or pieces, the back plate *a*, receptacle *b*, the bottom plate *d*, and the spring follower or clamp *f*, each of which may be struck up from single pieces of sheet metal. Of course the core *c'*, if used, is preferably a detached piece not secured positively to any

other part. One end of the clamp f^2 may be pointed or V-shaped, as shown at f^3 , so as to form a more efficient cutting edge for cutting off the worn-out portions of the strip of 5 igniting material.

The match-igniting strip c may be made of any suitable material, such as paper coated with a suitable chemical composition if the device is intended for safety-matches or with 10 sand or the like if the device is to be used in connection with ordinary parlor-matches.

Without attempting to set forth all the changes in form, construction, and arrangement of my device or all the uses to which 15 it may be applied, what I claim is—

1. A device of the class described, embracing in its construction a receptacle for matches, a spirally-coiled strip coated with material for igniting matches, and a spring arranged to 20 partly surround and to press inwardly toward the center of the strip to clamp and hold the strip from slipping when struck by a match, substantially as described.

2. A device of the class described embracing in its construction, a match-receptacle, a spirally-coiled strip for igniting matches, a support for said strip, and a clamp or follower arranged to normally exert a pressure against the outer spiral of the strip toward the center to hold it against displacement while being 25 scratched by matches.

3. A device of the class described, embracing in its construction, a back, a match-receptacle secured thereto, a plate hingedly connected with the back, a coiled strip of igniting material arranged between said receptacle 30

and said hinged plate in position to be struck by matches.

4. A device of the class described, embracing in its construction a back, a match-receptacle secured thereto, a coiled strip arranged below the match-receptacle, an inwardly-pressed clamp to hold said coiled strip against displacement, and a support arranged beneath said strip and connected with the back plate, 40 substantially as described. 45

5. A device of the class described, embracing in its construction a back plate slotted to form a spring-tongue, a bottom plate or support hingedly connected with said back plate 50 so as to normally project at right angles therefrom, a match-receptacle arranged above the hinged plate, a strip of igniting material arranged between the match-receptacle and the hinged plate, a spring-follower arranged to 55 press against the outside of the coiled strip to hold it in place.

6. A device of the class described, embracing in its construction a back plate, a match-receptacle secured thereto, a bottom plate arranged below the match-receptacle and movable with reference thereto, a coiled strip of igniting material arranged between the bottom plate and the receptacle, and a spring-clamp arranged to press against the outside of said 60 65 coiled strip, substantially as described.

In witness whereof I have hereunto set my hand this 31st day of March, 1903.

JACOB E. NEAHR.

In presence of—

GEO. N. GODDARD,
KATHARINE A. DUGAN.
